US00D855580S

(12) **United States Design Patent** (10) **Patent No.:** **US D855,580 S**
(45) **Date of Patent:** **** Aug. 6, 2019**

(54) **EARPHONE**

(71) Applicant: **Shenzhen Lingyin Technology Co., Ltd.**, Shenzhen (CN)

(72) Inventor: **Longhua Ma**, Shenzhen (CN)

(73) Assignee: **Shenzhen Lingyin Technology Co., Ltd.**, Shenzhen (CN)

(**) Term: **15 Years**

(21) Appl. No.: **29/636,046**

(22) Filed: **Feb. 6, 2018**

(51) LOC (12) Cl. **14-01**

(52) U.S. Cl.

USPC **D14/205**; D14/206

(57) **CLAIM**

The ornamental design for an earphone, as shown and described.

DESCRIPTION

FIG. 1 is a top perspective view of an earphone showing my new design;

FIG. 2 is a bottom perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of the encircled portion 9 in FIG. 1;

FIG. 10 is an enlarged view of the encircled portion 10 in FIG. 1;

FIG. 11 is an enlarged view of the encircled portion 11 in FIG. 2;

FIG. 12 is an enlarged view of the encircled portion 12 in FIG. 2;

FIG. 13 is an enlarged view of the encircled portion 13 in FIG. 3;

FIG. 14 is an enlarged view of the encircled portion 14 in FIG. 3;

FIG. 15 is an enlarged view of the encircled portion 15 in FIG. 4;

FIG. 16 is an enlarged view of the encircled portion 16 in FIG. 5; and,

FIG. 17 is an enlarged view of the encircled portion 17 in FIG. 6.

The broken lines are for the purpose of illustrating portions of the earphone that form no part of the claimed design.

The dot-dash broken lines encircling portions of the claimed design that are illustrated in enlargements form no part of the claimed design.

1 Claim, 17 Drawing Sheets
